UNITED STATES PATENT OFFICE.

SHERMAN FRENCH, OF PORTLAND, OREGON, ASSIGNOR OF ONE-FOURTH TO CLARA B. FRENCH, OF PORTLAND, OREGON.

FURNACE.

Application filed January 17, 1925. Serial No. 3,076.

This invention relates generally to furnaces which are used for heating the atmosphere in dwellings and living quarters, and particularly to furnaces for heating air, or water, or both.

The first object of this invention is to provide an exceedingly simple and efficient furnace which will be easy to manufacture, not easily damaged by heat or transportation and very simple to set up and keep in first class condition.

The second object is to provide heavy metal horizontal tubes of any desired shape, in which the air is heated and delivered to the supply pipes branching out to the various rooms.

These, and other objects, will become more apparent from the specification following as illustrated in the accompanying drawings, in which:

Figure 1 is a longitudinal vertical section through the device taken along the line 1—1 in Figure 2. Figure 2 is a transverse section taken along the line 2—2 in Figure 1. Figure 3 is a front elevation. Figure 4 is a horizontal section taken along the line 4—4 in Figure 1. Figure 5 is an enlarged plan of the shaking end of a portion of the grate bars. Figure 6 is a section taken along the line 6—6 in Figure 5. Figure 7 is a section taken along the line 7—7 in Figure 5. Figure 8 is a fragmentary enlarged plan of a section of the shaker bar or channel iron through which the shaker arms pass. Figure 9 is a section taken along the line 9—9 in Figure 8.

Similar numbers of reference refer to the same parts throughout the several views.

Referring in detail to the drawings, the furnace is illustrated in its preferred form with cast inner parts and a sheet metal outer casing, although this exact construction need not be followed, it being merely illustrated as one of the ways in which this furnace can be constructed.

In the drawings are shown a base 10 having a floor 11, inturned flanges 12, upper flanges 13 and a back 14, while across the frame 15 is secured an ash pit door 16 provided with a draft door 17 on the hinges 18.

On the base 10, which forms the ash pit of the furnace, is placed a fire pot wall 19, preferably lined with fire brick 20. Grate bars 21 form the floor for the fire pot and

journal in the grate bar frame 22, which 55 rests on the flanges 12 under the flanges 13. On the shanks 23 of the grate bars 21 are placed the levers 24 whose lower ends pass through the channel iron 25. The channel iron 25 is provided with slots 26 adapted 60 to receive the lower ends of the levers 24 which are secured on the shanks 23 of the grate bars 21. The channel iron 25 rests on the out-turned flange 27 of the grate bar frame 22. A ledge 28 is formed around the 65 upper side of the flange 13 and serves to hold the fire brick 20 in place.

Over the fire pot is placed a body whose sides 29 are shown as cast and having out-turned flanges 30 formed thereon and having 70 recesses 31 formed therein.

Flanges 30 are so aligned that the tubes 32 may pass through the opposite sides 29. The tubes 32 are preferably of heavy steel. One end of each tube 32 projects just 75 through the outside of a flange 30 and the other end of the tube 32 projects through the opposite flange 30 and through an opening in the outer side of the furnace and connects with the elbows 33, from which the 80 pipes may be led to the various rooms.

When the side frames 29 of the body are made of steel, the tubes 32 are preferably welded to the side frames thereby insuring an absolutely tight joint against smoke, or 85 else provided with a draw band (not shown), under which is placed suitable packing.

When a furnace is installed under conditions which require fewer air ducts than it 90 possesses flanges 30, it is only necessary to cap the end of the tube, or, if desired, omit the tube altogether and cap the flanges 30.

In the front 34 of the body is provided a flanged opening 35 which serves as an opening for the fire door 36 such as are in common use. In the back 37 of the body is provided a flanged opening 38 to which may be attached the smoke pipe 39. On top of the body is placed an auxiliary body 40, 100 across which is placed the transverse tubes 41 on whose projecting ends are placed the caps 42 from which may be led the pipes 43 connected with the usual hot water system. The auxiliary body is provided with 105 a cover 44.

Over the sides of the parts just described, and spaced therefrom, are the casing walls

45 and across the rear is placed a wall 46 provided with a cold air return duct 47, which may be in any convenient place.

5 A damper 48 is placed at the rear of the body just in front of the smoke outlet 38, and a rod 49, which passes through the front of the furnace, is attached to the upper side of the damper between the nuts 50. A sheet metal front 51 forms the front of the 10 furnace casing not occupied by the door frames.

A sand pan is formed by the casing cover 52 whose up-turned edges 53 are secured to the side walls of the casing.

15 The operation of this device is as follows: Fuel is placed on the grate bars 21 and the draft door 17 is opened, as well as the damper 48, which is swung to the position shown in full lines in Figure 1. The draft 20 is then directly through the pipe 39. When the fire is sufficiently started, the damper 48 is moved to the position shown in dotted lines in Figure 1 and the draft 17 is checked. The heat now circulates around 25 the tubes 32 and warms the air within same discharging it through the elbows 33, and takes in more air from within the casing, which air has just entered the intake pipe 47 and absorbed heat which is radiated 30 from the sides of the ash pit, fire pot and body.

If it is desired to heat a portion of the house with hot water, or to provide a supply of hot water for domestic purposes, the unit 35 40 is employed, which, of course, operates in the same manner as the air unit except that both ends of the tubes 41 project from the casing walls 45. If it is not desired to employ the water unit, a cover is placed directly over the air unit in place of the cover 44.

With the construction above outlined the cleaning process is entirely eliminated, since there is no place for soot or ashes to lodge.

45 It must be understood that many changes

in the details illustrated in this device may be made without departing from the spirit of my invention. The drawings, as above suggested, merely indicate a desirable form and serve to illustrate the principle underlying this furnace and the manner in which the various results are attained.

I am aware that many forms of furnaces have been constructed in the past, I therefore do not intend to cover such devices broadly but I do intend to cover all such forms and modifications as fall fairly within the appended claims.

I claim:

1. A furnace having, in combination, a 60 combustion chamber; a casing around said combustion chamber; and horizontal flues passing through said combustion chamber and having one end opening into the space between said casing and combustion chamber and the other end passing through said casing and connecting with a warm air conducting pipe.

2. A furnace having, in combination, an ash pit; a fire pot over said ash pit; a body 70 over said fire pot; an air-containing casing around said ash pit, fire pot and body; a plurality of horizontal flues passing through said body, one end of each flue passing through said casing and the other end of 75 said flue opening into the space between said body and casing.

3. A furnace having, in combination, an ash pit; a fire pot over said ash pit; a body over said fire pot; a cover over said body; a smoke pipe leading from said body; a casing around said ash pit, fire pot and body; a plurality of horizontal warm air delivery tubes passing through said body and casing and opening at one end into the space between said body and casing; and a damper 85 between said tubes and said smoke pipe opening.

SHERMAN FRENCH.
